PATENTED FEB. 6, 1906.

E. B. JARVIS.

REINFORCED CONCRETE.
APPLICATION FILED MAY 31, 1904.

UNITED STATES PATENT OFFICE.

EDGAR BEAUMONT JARVIS, OF TORONTO, CANADA.

REINFORCED CONCRETE.

No. 811,926.

Specification of Letters Patent.

Patented Feb. 6, 1906.

Application filed May 31, 1904. Serial No. 210,563.

To all whom it may concern:

Be it known that I, EDGAR BEAUMONT JARVIS, of the city of Toronto, in the county of York, in the Province of Ontario, Canada, have invented certain new and useful Improvements in Reinforced Concrete, of which the following is a specification.

My invention relates to improvements in reinforced concrete; and the object of the invention is to make a cheap, efficient, and scientifically-constructed truss to be incorporated in concrete beams, columns, or other supports, whereby the least amount of metal consistent with strength will be employed in the construction; and it consists, essentially, of a plurality of bars of increasing length located adjacently, having their ends bent obliquely, so that the bent portions incline toward the end of the beam or column, holes being provided in the extreme ends of the bars, through which a central rod passes, uniting them.

Figure 1 is a perspective view of a beam supported on a column partially broken away and in section to exhibit the construction of my truss. Fig. 2 is an enlarged detail showing one truss and the central rod. Fig. 3 is a section through *a b* in the truss before the concrete is placed about it.

In the drawings like letters of reference indicate corresponding parts in each figure.

A is the concrete beam, and *B* is one of the concrete columns on which it rests.

C, *C'*, and *C''* are bars of similar form, but of increasing length and located one above the other, as indicated in the drawings.

e and *f* are holes provided in the ends of the rods, through which a central rod *D* passes.

The various bars constituting one truss are bound together at suitable points, as *g*, by wire clamps or other suitable contrivances. In the column a plurality of similar trusses are located symmetrically about a central rod, as shown, preferably with a truss opposite each corner.

D' is a straight rod provided with a hole *h* in the end, which slips over the central rod of the supporting-column, insuring rigidity and forming a binding-tie. If the beam is continuous, a similar rod *D'* runs along the bottom of the second space, slipping in place on the rod of the supporting-column above *D'*. The oblique portions of the rods form the ties taking the tensile stress, the compressive stress being resisted by the cement, which is particularly strong in compression. The

greatest binding moment of the truss, both in the beam and post at the center, it will be seen in construction, is taken by the maximum depth of bars, such depth decreasing as the bars approach the end of the beam practically in proportion as the bending moment decreases. In the column it will readily be seen that the metal is placed in the most suitable place to prevent collapsing when the load is applied.

It will readily be seen from the form of truss that I have designed that a maximum stress is obtained in the concrete beam with a minimum weight of metal.

In Fig. 3 I show a wire or other suitable mesh *E*, which is stretched around the truss and forms a base for a coating of cement. After the cement is set it will be readily seen that a mold-box is formed into which the cement is poured, so as to make a solid mass or column. By this means the expense of putting up wooden forms is saved, which is an important desideratum.

What I claim as my invention is—

1. In cement columns in combination a plurality of trusses each consisting of a central rod and a plurality of bars of different lengths and located one above the other, having their ends bent obliquely and converging to the central rod said rod passing through the ends of all the bars as and for the purpose specified.

2. In cement structures, in combination a beam having in it a truss consisting of a central rod and a plurality of bars of different lengths, located one above the other having their ends bent obliquely, a column containing a plurality of like trusses secured to the central rod and a link-bar connecting the trusses in the beam and column as and for the purpose specified.

3. A strengthening truss or device for concrete structures comprising a frame composed of a plurality of sets of radially-arranged bars, each set consisting of a plurality of straight portions of different length secured together and having inwardly-inclined portions connected to the inwardly-inclined portions of the other sets, and a wire mesh encircling the sets of bars and in contact with the outer surface of the straight portions thereof, substantially as described.

EDGAR BEAUMONT JARVIS.
